UNITED STATES PATENT OFFICE.

CARLTON L. SMITH, OF SAGINAW, MICHIGAN, ASSIGNOR TO THE SAGINAW PLATE GLASS COMPANY, OF SAGINAW, MICHIGAN, A CORPORATION OF MICHIGAN.

AUTOMATIC GUARD FOR GLASS-CASTING TABLES.

1,184,144.

Specification of Letters Patent.

Patented May 23, 1916.

Application filed December 27, 1915. Serial No. 68,801.

To all whom it may concern:

Be it known that I, CARLTON L. SMITH, a citizen of the United States, residing at Saginaw, in the county of Saginaw and State of Michigan, have invented certain new and useful Improvements in Automatic Guards for Glass-Casting Tables; and I do hereby declare the following to be a full, clear, and exact description of the invention, such as will enable others skilled in the art to which it appertains to make and use the same.

This invention relates to improvements in machines used in the manufacture of plate glass and pertains to glass-casting machines of the type that comprises a casting table upon which the molten glass is poured, a roller adapted to travel over the table to roll the molten glass into a flat plate, and a leer or annealing oven, into which the plate is slid from the top of the table.

My improvement relates more specifically to a device employed in casting machines of the type mentioned, and known in the art as a "gun," that is to say, a device whereby the mass of molten glass flowing in front of the roller and traveling along with it is prevented from spreading too far sidewise and running off the edge of the table.

My invention comprises an improved construction of the gun, and devices whereby the gun, after traveling the length of the table in front of the roller is automatically raised clear of the glass plate, permitting the plate to be slid or stowed into the leer as soon as the rolling of the sheet is completed. Lifting the gun off the table at the end of each rolling, as has heretofore been common, is thereby rendered unnecessary.

By making it unnecessary to lift the gun off the table by hand at each rolling, important advantages are attained, namely, the operations of casting, rolling and stowing the plate into the leer are facilitated and safety to the operators is assured.

As is well known, the roller commonly employed is of great weight, usually several tons. It is usually rolled along the table by means of heavy winding chains operated by power. The roller exerts enormous force, in fact, sufficient to crush an arm or the body of an operator if he becomes caught between the roller and the table.

Slightly inclined ways called horns are usually provided at the front or leer end of the table, and the roller, when it approaches

the end of its travel, rolls up on these horns, rising sufficiently high to clear the sheet of glass which may then be stowed into the leer by passing beneath the roller. The gun, which usually consists of a vertically disposed plate of steel shaped at its rear edge to fit the periphery of the roller, is pushed forward by the roller as it moves to the front. The gun retains the wave of molten glass that travels ahead of the roller, preventing the glass from flowing over the trangs and the edges of the table. The gun also guides the glass to form straight edges on the finished sheet.

It is obvious that the gun is needed to perform the functions just mentioned during the forward travel of the roller; but when the end of the sheet is approached and before the roller starts up the incline of the horns the gun must be taken away. The time available in practice for the removal of the gun by hand is very short, and the quick removal of the gun has been accomplished by the operator who was obliged to stoop under the roller-actuating chain, pick the gun up by inserting a hook in a hole provided in the gun near its top, while seizing the forward end of the gun, and then lifting it clear of the roller and table. An expert was required for this work, because the gun and operator must be clear of the moving roller and chain before the roller started up the incline of the horn—a very dangerous operation. Therefore, to overcome these objections and to do away with the necessity of removing the gun by hand, my present improvement is devised.

My invention permits the gun to remain in contact with the roller clear to the end of travel of the roller, but toward the end of the travel, the gun, still in contact with the roller automatically rises clear of the glass, to permit stowing, and the gun does not have to be removed by hand. Moreover the gun performs its proper function of retaining and controlling the glass clear to the end of the rolling.

With these and other objects in view which will appear later in the specification, my invention consists in the devices described and claimed and the equivalents thereof.

In the drawings, Figure 1 is a side view, broken away in part, showing a casting table with the roller, gun and horn in place.

Fig. 2 is a rear end elevation of the casting table and roller. Fig. 3 is a perspective view of my improved form of gun and of the tilting plate by which the gun is automatically lifted after the rolling of the sheet is completed, in order to clear the glass sheet. Fig. 4 is an end view of the tilting plate and its support.

1 represents the usual casting table and 2 10 the slip table, which is a continuation of the casting table and connects the casting table to the leer, not shown.

3 is the roller and 4 is one of the usual pair of horns, upon which the roller rests 15 at the end of its travel.

5 is one of a pair of winding chains secured at one end to the roller 3 and passing around a suitable sheave 6 at the end of the table.

20 In Fig. 1 the initial position of the roller 3 is shown in full lines, and its position after the rolling is completed is indicated by dotted lines.

7, 7 is a pair of flat bars or tracks termed 25 in the art "trangs," upon which the roller 3 travels, the thickness of the trangs gaging the desired thickness of the sheet of glass.

The gun 8 is formed of a plate of steel having a forward extension carrying a 30 channel-shaped shoe 9 that fits loosely over the trang 7 and serves as a guide for the gun while the gun is being pushed along in front of the roller.

In applying my improvement, I secure to 35 the upper part of the gun by riveting or otherwise, a thrust plate, bracket or equivalent bearing member 10 offset laterally from the plane of the gun 8. The rear edge of the bracket, as well as the rear edge of the 40 upper part of the gun, bear against the periphery of the roller, but the lower part 11 of the rear edge of the gun is preferably not in contact with the roller.

The bracket and the upper part of the 45 gun being in contact with the roller, these two contact points take the thrust of the roller. The gun is thereby maintained in its vertical position even after the shoe 9 has passed beyond the trang 7 and is no longer guided by the trang 7, for a purpose which will now be explained.

When the roller 3 is moving up the horns 4 to the raised position indicated by dotted lines in Fig. 1, my improvement enables the 55 gun to be automatically lifted a sufficient height above the table to permit the sheet of glass to be "stowed" or slid across the slip table 2 into the leer in the direction indicated by the arrow in Fig. 1. The 60 means by which the gun is automatically lifted is indicated in Figs. 1, 3 and 4, where 12 is a tiltable plate located at the side of the casting table and in the path of travel of the gun, the plate 12 being preferably 65 mounted on a suitable bracket 13, or its

equivalent, carried by the side frame or housing of the table 1.

The tiltable plate 12 preferably has its edge nearest the roller beveled to snugly fit the surface of the casting table. The plate 70 is tiltably supported at a point 12^a above the path of travel of the glass and is balanced so that its beveled edge normally rests on the surface of the table 1, as shown by the dotted lines in Fig. 1. 75

In operation, the roller 3 moving up the inclined horn 4 pushes the gun 8 before it. The shoe 9 of the gun travels beyond the end of the trang 7 and slides up the inclined plate 12 and the upright position of the gun 80 and its proper direction of travel are maintained by the alignment secured by the double contact of the upper part of the gun and of the thrust plate 10 with the periphery of the cylindrical roller as previously described. 85

To enable the gun to easily slide up the inclined plate 12 I prefer to slightly bevel or round the rear edge of the shoe 9, as at 14. 90

While the roller travels up the horn incline 4 the gun 8 and the tiltable plate assume a horizontal position above the table 1, as indicated at 15 in Fig. 1. When the roller, gun and tiltable plate are in this position the sheet of glass may be slid forward or stowed into the leer. The roller may then be returned to its original position at the back end of the table and the gun and tiltable plate automatically return to their inclined position 12. The gun may afterward be slid back along the trang 7 to its initial position against the roller, and the table is ready to receive another charge of molten glass. 95

By this device the quality of glass is improved, because it is not necessary to remove the gun during each rolling and consequently there is no liability of threads of molten glass adhering to the gun and being picked up with it and deposited on the surface of the trangs 7, as has heretofore frequently been the case. It is obvious that a thread of glass, if deposited on the surface of the trang will lift the roller, causing a ridge or roller mark to be formed on the plate. I reduce this liability, it being unnecessary with my device to remove the gun by lifting it off sidewise as heretofore. 100

Some molten glass is saved by using my device, since all the material goes into the plate, whereas, when the gun was lifted off at each rolling more or less of the glass adhered to the gun and was removed with it, and the glass so removed was lost. Furthermore, the plate is left with an even edge, since the roughing of the edge caused by removing the gun is avoided. One of the main advantages of my improvement is, however, the avoidance of accident and injury to the operators. 105

Having thus described my invention, what I claim and desire to secure by Letters Patent is:

1. The combination of a casting table, 5 horns, and a roller, a gun actuated by said roller, an offset bearing member secured to the upper part of said gun and engaging the periphery of the roller, the rear edge of said gun shaped to be out of contact with 10 the roller, a shoe secured to the side of the gun, the forward bottom edge of said shoe rounded, a tiltable plate mounted above said table in the path of travel of the gun, said plate being normally inclined downward to 15 receive the gun and adapted to be moved to horizontal position by the movement of the roller when the roller travels up the horns.
2. The combination of a casting table, 20 horns, a traveling roller, a gun actuated by said roller, an offset bearing member secured to said gun and bearing against the periphery of the roller, a shoe secured to the side of the gun, and a tiltable plate mounted 25 above said table in the path of travel of the gun, said plate being normally inclined downward to receive the gun and adapted to be moved to horizontal position by the

movement of the roller when the roller travels up the horns.

3. The combination of a casting table, horns, a traveling roller, a gun, an offset bearing member carried by said gun and adapted to engage the periphery of the roller, to sustain the gun in vertical position 35 throughout the travel of the roller, and means disposed near the end of the forward travel of the roller and adapted to automatically lift the gun clear of the table for the purposes set forth. 40

4. The combination of a casting table, horns, a traveling roller, a gun adapted to engage the periphery of the roller and to maintain contact therewith throughout the entire forward travel of the roller, and 45 means located near the end of the forward travel of the roller and adapted to automatically raise the gun clear of the table while the gun is in contact with the roller.

In testimony whereof, I affix my signature in presence of two witnesses.
